Inventor

UNITED STATES PATENT OFFICE

FRANKLIN F. CHANDLER, OF LA FAYETTE, INDIANA, ASSIGNOR TO ROSS GEAR & TOOL COMPANY, OF LA FAYETTE, INDIANA, A CORPORATION OF INDIANA

LEVER

Application filed December 13, 1926. Serial No. 154,568.

This invention is a novel improvement in levers to be attached to tubes or rods, and means for attaching the levers so that all of the strains on the levers due to the attachment shall be tension strains that will not tend to deform the original shape of the lever.

The principal object of the invention is to provide a simple and efficient lever, preferably formed of a metal stamping and adapted to be securely attached to a tube or rod of circular or cylindrical cross-section without having to cut key-ways or slots therein; and to provide novel attaching devices so designed that when the lever is secured to a tube or rod all of the internal strains in the lever due to its attachment to the tube or rod will be tensile strains and not bending or transverse strains which would tend to deform the original shape of the lever.

Another object of the invention is to provide a stamped metal lever so designed as to shape and attaching means that it can be readily removed radially from a tube or rod, thereby obviating the necessity of having to slide the lever over the end of the tube or rod when attaching or removing same therefrom.

Other objects of the invention are to produce a stamped metal lever which can be readily secured in any desired position on a tube or rod and as readily detached; also a lever locking means that can be applied from either side of the lever, and will effectually secure the lever to the tube or rod when inserted from either side; also to provide a lever and locking devices therefor in which the reaction of the locking key on a thin tube will not depress or cave in the tube by the pressure of the key on the tube; and also to provide a lever of relatively great strength, and locking devices therefor, which can be produced, economically from a minimum of original metal with practically no waste in fabrication. Other minor objects of the invention will be hereinafter set forth.

I will first explain the invention with reference to the accompanying drawing which illustrates practical embodiments thereof and will enable others familiar with the art to adopt and use the same; and then summarize in the claims the novel features of construc-

tion, and novel combinations of parts for which protection is desired.

In said drawings,—

Fig. 1 is a side view of one form of lever attached to a tube or rod by the novel locking means;

Fig. 2 is a similar view of the opposite side of Fig. 1;

Fig. 3 is a transverse section on the line 3—3, Fig. 2;

Fig. 4 is a transverse section on the line 4—4, Fig. 2;

Fig. 5 is a view similar to Fig. 3 showing a spacer used with the modified form of lever;

Fig. 6 is a view similar to Fig. 3 showing a slight modification of the lever;

Fig. 7 is a view similar to Fig. 4 of the modified lever shown in Fig. 5;

Fig. 8 is a sectional view similar to Fig. 4 illustrating the employment of a case lever;

Fig. 9 is a side view of Fig. 8; and

Fig. 10 is a detail of a spacer detached.

The lever as shown in Figs. 1 to 7 is preferably formed of a sheet metal stamping of any desired length and thickness having a return bend at one end, the leg 1^a of the bend lying parallel with the main body of the lever. The leg 1 may if desired be of same length as the body. The body 1 can be shaped and proportioned according to the particular use for which the lever is designed.

As shown in Figs. 6 and 7 in the body 1 and leg 1^a are opposite axially aligned openings 1^b, adapted to engage a tube or rod T which extends therethrough. The diameter of the openings 1^b is preferably such as to neatly but slidably engage the tube to which the lever is to be attached. The axes of opening 1^b are preferably located a distance from the center of the inner face of the bend of the lever slightly less than the distance between the inner faces of the body 1 and leg 1^a of the lever, for the purpose hereinafter specified.

As shown in Figures 3 to 5, the openings 1^b in the leg and body are connected by a slot 1^c which is equal in width to the diameter of the openings, and this slot extends through the bend of the lever and practically produces a bifurcated bend.

As shown in Figures 8 and 9 the lever 1^x is made of cast or die-stamped metal, and has a bifurcated end lax adapted to engage a pipe or rod, and provided with opposed openings 1^{bx} in the bifurcations for the engagement of the fastening gib as hereinafter referred to. The bifurcated construction enables the lever to be directly applied to the tube T, radially thereof, at any point, whereas the lever shown in Figures 6 and 7 could only be applied to the tube by slipping it endwise thereover. For some constructions and purposes the bifurcated bend levers, as in Figures 3 to 5, and 8 and 9, would be preferable; for other purposes the non-bifurcated bend levers such as shown in Figures 6 and 7 would be preferable, the latter being stronger.

Any one of such levers when applied to the tube and moved to the desired position can be firmly secured thereto by means of a clamp or gib 2 which is inserted between the inner wall of the bend of the lever and the tube as shown in the drawings.

The gib 2 is preferably formed of drawn rod metal of a diameter equal to the distance between the body 1 and leg 1^a of the lever, said gib 2 being adapted to be entered in the bend of the lever and between it and tube T when the latter is engaged with the openings 1^b. One end of gib 2 is preferably reduced as at 2^a, and threaded for engagement of a nut 2^b. The body of gib 2 is formed with portion 2^c extending inward from the threaded end 2^a toward the opposite end of the gib and a tube clamping portion 2^d. The portion 2^c should be of such depth as to permit the key to be inserted in the lever between the bend and the adjacent wall of the tube T, the clamping portion 2^d being disposed adjacent the tube T.

The clamping portion 2^d of the gib is adapted to engage the tube T when the gib is inserted in place as shown in Figs. 3 to 9. The threaded portion 2^a of key 2 extends beyond the lever and carries nut 2^b. And when the nut 2^b is tightened the gib 2 will be drawn through the bend of the lever and transversely of the tube T until the wedge portion 2^d of the gib binds against the tube T and effectually binds the lever to the tube. The gib can be caused to clamp the tube with great force, and will lock the lever to the tube and prevent its displacement thereon either longitudinally or rotatorily.

Preferably, a washer is inserted between nut 2^b and the legs 1, 1^a of the lever such as shown in Figs. 1 to 7, said washer 3 having a projection 3^a extending from its periphery of width preferably equal to the diameter of the gib 2, the said projection 3^a being bent slightly out of the normal plane of washer 3 and adapted to enter between the body 1 and leg 1^a beside tube T as shown in the drawings; said projection 3^a prevents rota-

tion of the washer 3 and properly spaces the leg 1^a with respect to the main portion 1 of the lever.

When bifurcated levers such as shown in Figs. 3 to 5 are used a spacing sleeve 4 (Figs. 5 and 9) is preferably placed on the gib in the bifurcation of the bend of the lever; said spacing sleeve 4 being so formed so as to permit engagement of the clamping portion of the gib with the tube T as above described, but will prevent any lateral distortion of the bifurcation of the bend under the pressure exerted by the nut and gib.

Levers and fastenings therefore constructed in accordance with my invention can be quickly applied to or removed from a rod or tube. The locking gib can be inserted equally well from either side of the lever. The action and the reaction between the gib, lever, and tube when the gib is tightened will produce only tensile strains in the lever and not bending strains; so that the lever when locked in position will not be deformed by the action of the locking devices.

With levers as shown in Figs. 6 and 7 the pressure of the gib will not depress or cave-in a thin tube at the spot where the gib contacts with the tube, as the tube neatly fits in the holes 1^b, and when the gib is tightened the pressure which would tend to distort the thin tube is uniformly resisted by the circular holes in the lever.

I claim:—

1. A lever having a recess in one end for engagement with a rod or tube; and opposed openings at opposite sides of this recess; a gib adapted to be entered between the openings and the rod or tube; a washer in one end of the gib having a projection adapted to engage the recess, and means to cause the gib to clamp the lever on the shaft.

2. A lever comprising a U-shaped body having opposed openings in its legs for engagement with a rod or tube, and having a slot connecting said openings whereby the lever may be engaged and disengaged radially of the rod or tube; and a locking gib adapted to be entered transversely of the openings between the bend of the lever and the rod or tube and engage the bend at opposite sides of said slot.

3. In combination with a lever as set forth in claim 2, a washer on the gib having a projecting portion extending between the legs of the body.

4. In combination with a lever as set forth in claim 2, a spacer on said gib extending between the walls of the slot.

5. A lever comprising a U-shaped body having opposed openings in its legs adjacent the bend for engagement with a rod or tube, and having a slot extending inwardly from the bend connecting said openings whereby the lever may be engaged and disengaged radially of the rod or tube; a locking gib adapted to be

entered transversely of the slot between the bend of the lever and the rod or tube and a spacer on said gib extending between the walls of the slot

5 6. In combination with a lever as set forth in claim 5, a washer on the gib having a projecting portion extending between the legs of the body.

10 7. In combination with a lever as set forth in claim 5, a spacer on said gib extending between the walls of the slot.

15 8. A lever comprising a U-shaped body having opposed openings in its legs for engagement with a rod or tube, and having a slot extending inwardly from the bend connecting said openings whereby the lever may be engaged and disengaged radially of the rod or tube; a locking gib adapted to be entered between the bend of the lever and the 20 rod or tube; a washer on the gib having a projecting portion extending between the legs of the body; and a spacer on said gib extending between the walls of the slot.

25 In testimony that I claim the foregoing as my own I affix my signature.

FRANKLIN F. CHANDLER.
